UNITED STATES PATENT OFFICE.

THOMAS E. DIMELOW, OF PHILADELPHIA, PENNSYLVANIA.

ARTIFICIAL TOOTH.

1,070,785.

Specification of Letters Patent. Patented Aug. 19, 1913.

Application filed March 6, 1913. Serial No. 752,433.

To all whom it may concern:

Be it known that I, THOMAS E. DIMELOW, a citizen of the United States, residing at Philadelphia, in the county of Philadelphia and State of Pennsylvania, have invented 5 certain new and useful Improvements in Artificial Teeth; and I do declare the following to be a full, clear, and exact description of the invention, such as will enable 10 others skilled in the art to which it appertains to make and use the same.

This invention relates to artificial teeth of the class having a flat back with an obliquely formed socket extending from said 15 back toward the front of the tooth and which is adapted to be secured to a straight flat backing having a pin or pins projecting therefrom at an angle to the longitudinal plane of the same.

20 The object of the invention is to provide simple and efficient means for attaching the backing to the tooth whereby a large holding surface for the tooth is afforded and whereby pressure will be relieved to a large 25 extent from the fastening means and evenly distributed throughout the tooth and upon the backing.

With these and other objects in view, the invention consists of certain novel features 30 of construction, and the combination and arrangement of parts as will be more fully described and claimed.

In the accompanying drawings: Figure 1 represents a vertical section of a tooth constructed in accordance with this invention; 35 Fig. 2 is a front view of the backing plate employed forming a part of this improved tooth; Fig. 3 is a perspective view of the fastening element used for connecting the 40 backing to the tooth.

In the embodiment illustrated a flat backing or plate 1 is shown having a longitudinally extending slot 2 in which is adapted to be inserted and secured a fastening element in the form of a staple 3 having a reduced central portion or a cross bar 4 which is inserted in the slot 2 and held therein by solder and when in position the outer face of this reduced cross bar of the staple 45 extends flush with or projects beyond the outer face of the backing as shown clearly in Fig. 1. The legs 5 and 6 of this staple

are arranged obliquely to its back or cross bar 4 and the inner ends thereof forming shoulders 7 which abut against the inner 55 face of the plate 1 as shown in Fig. 1. These obliquely disposed legs 5 and 6 are designed to be inserted in correspondingly arranged sockets 8 and 9 formed in a tooth 10 and are secured therein by cement or other suitable material in the usual manner. These sockets 8 and 9 which are spaced longitudinally extend from the rear face of the tooth toward the front thereof at an oblique angle. These pin receiving sockets are in the same 65 position, same angle and of the same depth in all relative teeth or those of a kind, and for this reason the backing plate, for one tooth will fit any of the relative teeth therefor, thus making the teeth interchangeable. 70

The pins or staples are entirely independent of the backing plate and with the aid of the tooth a staple is set in position and the bar thereof temporarily fastened to the plate after which operation the tooth is removed and the operator proceeds to finish the work on the bridge. About the last work to be done is to put the tooth back on the pins or legs of the staple and which is securely fastened to said legs by cement 80 or other suitable adhesive material.

While I have described my invention with more or less minuteness as regards details and as being embodied in certain precise forms, I do not desire to be limited thereto 85 unduly any more than is pointed out in the claims. On the contrary, I contemplate all proper changes in form, construction and arrangement, the omission of immaterial elements and substitution of equivalents as 90 circumstances may suggest or render expedient.

I claim as my invention:

1. An artificial tooth having obliquely formed sockets, a backing having obliquely 95 carried pins adapted to enter said sockets, said pins being in the form of an angled staple carried by said backing, the body portion or cross bar of said staple being reduced and said backing having a slot to 100 receive the reduced portion of the staple.

2. An artificial tooth having spaced sockets, a backing having a slot therein, a staple having the cross bar thereof reduced

and secured within said slot, shoulders formed on the inner ends of the legs of said staple and adapted to abut against the inner face of said backing plate, the legs of said staple being arranged obliquely and adapted to fit in the sockets of the tooth.

In testimony whereof I have hereunto set

my hand in presence of two subscribing witnesses.

THOMAS E. DIMELOW.
